C. R. ECKBERG

LIQUID DISPENSER

Filed May 28, 1928

Inventor
Curtis R Eckberg

By Roy H. Olson
Attorney

UNITED STATES PATENT OFFICE.

CURTIS RALSTON ECKBERG, OF CHICAGO, ILLINOIS.

LIQUID DISPENSER.

Application filed May 28, 1928. Serial No. 281,154.

My invention relates to liquid dispensers and more particularly to dispensing devices which are adapted to be used for supplying ink to drawing pens and the like.

It has heretofore been the common practice to supply ink to drawing pens and the like by means of the conventional quill secured to the underside of the usual ink bottle stopper. This quill arrangement has certain unsatisfactory features. One of these outstanding unsatisfactory features resides in the fact that considerable inconvenience is sometimes experienced by the user in attempting to remove the stopper from the bottle. This inconvenience is often occasioned as a result of the drying or caking of the ink which has collected within the neck of the bottle. The very fact that the stopper must be removed each time that a pen is to be filled with a supply of ink, is in itself a decided inconvenience. Also, it sometimes happens, in instances where the stopper is continuously removed at frequent intervals, that an appreciable portion of the ink solution is evaporated and this results in the thickening of the ink remaining within the bottle. It often happens that the stopper is inadvertently permitted to lie on the desk or drawing board for a considerable period, thus leaving the ink exposed to the atmosphere and subjecting the quill and stopper to the possibility of loss and breakage.

In general, one of the primary objects of my present invention is to obviate the above mentioned and other inconveniences which have heretofore been experienced and to this end I propose to provide a liquid container or bottle equipped with means which enables a predetermined quantity of liquid to be dispensed by merely inverting the container.

Another and more specific object of my invention is to provide a dispensing device which may be very effectively employed to supply ink to drawing pens and the like, said device including a container or bottle having means carried by a stopper which will permit a drop of ink to be delivered into a position to be received by a drawing pen when said container or bottle is manually inverted.

A still further object of my invention is to provide a conveniently operable ink dispensing device of economical and simple construction which includes a container or

bottle having a stopper in the neck thereof, and carried by said stopper are a pair of tubes, one of said tubes being designed to admit a predetermined quantity of air into the container when said container is inverted, thereby permitting a predetermined quantity of ink to flow from the container through the other tube.

In addition to the above mentioned characteristics, my invention contemplates the provision of an ink container having a stopper in the neck thereof, said stopper supporting a pair of tubes, one of said tubes extending well into the container and capped with a pliable sack, the other tube just reaching into the container and formed at its outer extremity so as to function similarly to the usual quill, the sack carried by one of the tubes serving to permit the introduction of a predetermined volume of air into the container upon inverting the same, thereby causing a predetermined quantity or drop of ink to be delivered to the quill portion of the other tube in a position to be received by a drawing pen or the like.

These and other objects will be more apparent from the following detailed description when considered in connection with the accompanying drawing, wherein:

Fig. 1 is a vertical sectional view taken centrally of a dispensing device embodying features of my invention; and

Fig. 2 is a sectional view similar to Fig. 1 showing the device in an inverted position, a drawing pen indicated by dot and dash lines being shown in association with the quill portion of one of the tubes to receive a supply of ink therefrom.

Referring now to the drawing in detail, wherein I have employed like numerals to designate similar parts throughout the various figures, it will be observed that certain features of my invention reside in a container or bottle 2 having a body portion 4 and a neck portion 6 extending upwardly therefrom.

A stopper 8 comprised of suitable resilient material such as cork, rubber or the like, is fitted within the neck 6. Said stopper is provided with a suitable flanged head 10 to facilitate the insertion and removal thereof.

Fitted within and extending through a pair of parallel apertures formed in the stopper 8 are a pair of tubes or conduits 12 and 14. The tube 12 is flush at its outer

extremity with the outer surface of the head of the stopper, the inner extremity thereof terminating well within the bottle 2 and capped with a pliable or flexible sack 16. 5 This sack 16 may be of any suitable pliable material such as thin rubber material or the like. I prefer to use such material which may be readily slipped over the end of the tube 12, the flexibility or resiliency of the 10 material being sufficient to cause it to securely adhere to the tube. In some instances it might be desirable to employ a small amount of adhesive to secure the sack to the tube. When the bottle 2 occupies its 15 normal upright position as shown in Fig. 1, the sack 16 will be submerged within the ink 18 and the pressure of said ink will be sufficient to collapse said sack.

The tube 14 is shorter than the tube 12, 20 the lower end thereof terminating just below the stopper 8, well above the surface of the ink 18. The outer end 20 of the tube 12 is shaped similarly to the conventional quills commonly employed with stoppers of 25 ink bottles and is similarly adapted to present ink to a drawing or ruling pen 22, indicated by dot and dash lines in Fig. 2.

From the foregoing description it will be understood that in order to fill the drawing 30 pen 22 it is only necessary for the user to invert or tilt the bottle 2 so that it will occupy the position shown in Fig. 2. As already pointed out, the sack 16 remains collapsed as shown in Fig. 1, when the bottle 35 occupies the normal upright position. When said bottle is inverted and the ink attempts to flow through the tube 14, said flow is retarded by reason of the air trapped within the bottle above the surface 40 of the ink. Obviously as the ink begins to flow through the tube 14 from within the bottle, upon the tilting thereof, the trapped air will become rarefied and hence the pressure externally will be in excess of that 45 within the bottle. This will positively prevent the ink from reaching the quill portion 20 of the tube 14 unless the pressure within the bottle is increased. It will thus be clear that I provide the sack 16 for the purpose 50 of permitting the introduction of a small or predetermined amount of air to increase the pressure above the ink sufficiently to cause a small amount or drop 24 (Fig. 2) of ink to flow to the quill portion of the tube 55 14. The amount of air introduced within the bottle will of course be determined by the size of the sack which is employed and this size will be governed by the quantity of ink which it is desired to have delivered to 60 the quill. Thus my invention provides a very simple and effective device for presenting a predetermined quantity of ink to a quill without the necessity of removing the stopper.

65 The only place at which the ink 18 is ex-

posed to the atmosphere is through the tube 14 and the opening within this tube can be made small enough so that the effects of subjecting the ink to the atmosphere are negligible. In this way the supply of ink 70 always remains in a splendid, flowable condition and the difficulties heretofore experienced will be obviated. The stopper 8 may very easily be removed for the purpose of filling the bottle and it will be clear that in 75 shipping or packing the bottle it is only necessary to have the tube 14 forced downwardly into the stopper so the quill portion 20 will clear the upper surface of the container, thereby permitting the usual sealing cap (not shown) to be clamped in covering relation with respect to the stopper. It will thus be apparent that my invention 80 contemplates the provision of an ink dispensing device which is not only effective 85 in operation but which is also of a very practical and economical construction.

What I claim as my invention and desire to secure by Letters Patent of the United States is:

1. In a liquid dispensing device, a container having an opening to permit the discharge of liquid therefrom, and means which is responsive to the tilting of the container to effect an increase in pressure within the container, to thereby cause a predetermined amount of liquid to be dispensed through the discharge opening.

2. In a liquid dispensing device, a container having an opening to permit the discharge of liquid therefrom, and a flexible means supported within the container which is operable in response to the tilting of the container to effect an increase in pressure within the container, to thereby cause a predetermined amount of liquid to be dispensed through the discharge opening.

3. In a liquid dispensing device, a container provided with an opening to permit the discharge of liquid therefrom, and means adapted to expand within the container in response to the tilting thereof, to thereby increase the pressure therein sufficiently to cause a flow of liquid through the discharge opening.

4. In a liquid dispensing device, a container having a discharge opening, and an apertured member extending into the container having an expandible member traversing the inner end thereof, said expandible member being operable in response to the tilting of the container, to increase the pressure therein sufficiently to cause a flow of liquid through the discharge opening.

5. In a liquid dispensing device, a container having a discharge opening, an apertured member extending into the container, and an expandible membrane covering the inner end of the apertured member, the other end of said member being open, said mem-

brane being adapted to expand when the container is tilted so as to effect the flow of liquid through the discharge opening.

6. In a liquid dispensing device, a container, a liquid discharge device extending outwardly from the container, an elongated apertured member for establishing communication between the outer atmosphere and the inside of the container, and an expandable sack carried at the inner end of the apertured member, said sack being adapted to collapse when the container occupies its normal upright position and to expand when the container is tilted, so as to effect the discharge of liquid through the discharge device.

7. In a liquid dispensing device, a container, a removable stopper therefor, a tubular member extending through the stopper and into the container, an expandible

membrane covering the inner end of the tubular member, and a second tubular member extending through the stopper and terminating well above the surface of the liquid when the container occupies a normal up-right position.

8. In a liquid dispensing device, a container, a removable stopper therefor, a tubular member extending through the stopper and well into the container, an expandible membrane covering the inner end of the tubular member, and a second tubular member lodged within an aperture provided in the stopper, the outer end of said second mentioned tubular member being quill-shaped and adapted to be used for feeding liquid such as ink to drawing pens.

In witness whereof, I have hereunto subscribed my name.

CURTIS RALSTON ECKBERG.
